UNITED STATES PATENT OFFICE.

ALFRED SCHWARZ, OF NEW YORK, N. Y., ASSIGNOR TO WILLIAM SCULLY, TRUSTEE, OF BROOKLYN, NEW YORK.

ROTARY ENGINE.

1,239,829.

Specification of Letters Patent. Patented Sept. 11, 1917.

Application filed June 11, 1915. Serial No. 33,435.

To all whom it may concern:

Be it known that I, ALFRED SCHWARZ, a subject of the Emperor of Germany, residing at New York, in the county and State of New York, have invented certain new and useful Improvements in Rotary Engines, of which the following is a full, clear, and exact description.

The invention which constitutes the subject matter of this application relates to an engine of the wobbling piston type; or in other words to a rotary engine provided with an outer cylinder which rotates around a central fixed shaft. The invention, as will obviously appear from the detailed description below, is capable of use in connection with steam engines, internal combustion engines, air compressors, water or oil pumps, as a fluid gear, and for other purposes. The invention broadly speaking comprises a rotary cylinder and piston eccentrically mounted with respect to each other in combination with means for eliminating practically all friction of the parts connecting said piston and cylinder and which parts divide the space between the said piston and cylinder into a plurality of piston spaces. For the sake of clearness however I have chosen to illustrate only one embodiment of the invention, and this embodiment is in connection with a simple form of steam engine in which—

Figure 1 is a longitudinal section.

Fig. 2 is a cross section taken on the line C—D of Fig. 1.

Referring to the drawing in detail the reference numerals 10 and 11 designate suitable standards upon which the motor is supported, the motor in this instance being one particularly adapted to be operated by the expansive force of steam. The upper end of the standard 10 is provided with a bearing 12 in which is fixed by a set-screw 13 a shaft 14 provided with an intake through which steam is admitted to the motor. The standard 11 is provided with a similar bearing 15, in which is fixed, as by a set-screw 16, a hollow shaft 17 through which the gases or steam is exhausted from the engine.

The shaft 14, in the construction shown, is in alignment with and connected to the shaft 17. This connection is preferably a screw-threaded one to permit of longitudinal adjustment of one with respect to the other. Stationary members 18 and 19 are fixedly

and eccentrically mounted upon the shafts 14 and 17 respectively and serve as bearings for the heads 20 and 21 of the cylinder 22. These members 18 and 19 are circular in cross-section and the cylinder 22 is adapted to rotate about the geometrical center of the same. It will therefore be understood that the shafts 14 and 17 are eccentrically positioned with respect to the cylinder 22. Rotatably and concentrically mounted upon the shafts 14 and 17 is what I prefer to call a primary piston 23 and operating in conjunction with the primary piston and the outer cylinder is a plurality of secondary pistons 24 reciprocating radially in the chambers E, F, G and H provided therefor and located in the primary piston. The outer ends of these secondary pistons are pivotally connected to arcuate members 25 which have a limited movement circumferentially about the interior of the cylinder 22. To this end the outer edges of the secondary cylinders are provided with dovetail members 26 which pivotally connect the pistons 24 and the arcuate members 25. The ends of each of these arcuate members slide circumferentially within the arcuate spaces 27 formed by the shoulders 28 and 29 of the arcuate members 30 in conjunction with the outer cylinders 22 to which said arcuate members 30 are secured.

The chambers of the primary piston divide the latter into segmental sections 32, 33, 34 and 35 and these sections in conjunction with the pistons and the outer cylinder define four piston spaces A, B, C and D, to which steam is admitted through the intake port 36 and from which steam is discharged through the exhaust port 37.

It will be understood that the outer cylinder, and the primary and secondary pistons have different axes of rotation resulting therefore in a differential movement with respect to each other; in other words the primary piston is eccentrically located with respect to the outer cylinder 22. Owing to the eccentric arrangement and the connection of the secondary pistons with the outer cylinder the size of the piston spaces increases from minimum to maximum and decreases from maximum to minimum during each complete rotation of the cylinder 22, as will be understood.

Projecting inwardly from the cylinder heads 20 and 21 are a plurality of keys 38, 110

preferably one for each segmental section, which engage at all times with the inner circumferential wall of the recesses 39 when the engine is in operating condition and 5 cause each and every point on the primary piston to describe a circle during a complete rotation of the primary piston. These keys therefore establish a definite relation between the cylinder and piston. Of course the 10 position of these keys is determined by the eccentricity of the primary piston but if desired the cylinder heads may be provided with a number of key holes into which the keys may be inserted, or the keys may themselves be mounted upon adjustable members 15 and adjusted to the eccentricity of the primary piston. It will also be understood that the eccentricity of the primary piston is determined in the first instance by the position 20 of the stationary eccentrics 18 and 19. The ends of the arcuate members 26 project into recesses 29 formed in the cylinder heads 20 and 21. The secondary pistons therefore have a definite position with respect to the 25 cylinder.

The operation of the device is as follows: There are, in this particular embodiment of the invention, four piston spaces A, B, C and D which are defined by the outer cylinder 22, the primary piston 23 and the secondary pistons 24 the latter in this instance being rectangular in shape. The fluid for operating the engine is admitted from a suitable supply through the intake port 36 30 and through the ports 40 are 41 into the piston space A and piston chamber E respectively. In the position shown in Fig. 2 the intake port 36 at this instance is also in communication with piston space B and 35 piston chamber F through ports 42 and 43 respectively. However the ports 44, 45, 46 and 47 leading to the piston spaces C and D and piston chambers G and H are cut off from the intake port 36, but corresponding 40 ports are now in free communication with the exhaust port 37 the latter being placed at the opposite end of the cylinder 22 and on the side of the shaft 15 opposite to the port 36 in shaft 14. The ports 36 and 45 45 extend about half way around the shafts 14 and 15 respectively and it will be apparent that each port is in communication with each piston space for substantially one-half rotation of the primary piston. The 50 steam or other fluid admitted to the piston space A cannot escape because the exhaust port thereto is closed. The steam therefore acts against the secondary piston 24 and causes a revolution of the secondary pistons 55 in unison with the primary pistons and cylinder 22. Each division or part of the engine goes through the same cycle of operations. So far as I am aware no method of 60 keying the piston to the cylinder has been devised heretofore. This arrangement not

only establishes a proper relation of one member to the other and prevents one member from over-running the other, but also permits free movement of both members to perform the necessary mechanical motion. 70 The arrangement and the construction of the secondary piston and the mechanism associated therewith results in a radial movement only of the secondary pistons with respect to the center of rotation of the primary piston. As a further result of my construction it will be apparent that it is unnecessary to provide a fluid-tight connection between the arcuate members 26 and the outer cylinder 22 as the steam pressure behind the 80 pistons suffices to maintain the said members in fluid tight engagement with the bottom of the recesses 29.

To reverse the engine, in the construction illustrated, steam is admitted in the opposite 85 direction; that is to say the exhaust port becomes the intake port and vice versa.

What I claim is:

1. A rotary engine, comprising a primary piston and a cylinder or casing surrounding 90 said piston, said piston and cylinder being rotatably and eccentrically connected to each other, a plurality of secondary pistons slidably connected to said primary piston and slidably engaging said cylinder thereby defining a plurality of piston spaces between the inner wall of the outer cylinder and the outer wall of the primary piston, and means for admitting fluid behind said secondary pistons and to each of said piston spaces. 100

2. In a device of the class described, an outer cylinder and a primary piston eccentrically mounted therein and adapted to have a differential rotation with respect thereto, and a plurality of secondary pistons slidably engaging the outer cylinder and mounted in and movable with respect to the primary piston, in combination with a plurality of keys projecting inwardly from each head of said cylinder and engaging 110 with the primary piston to prevent one from overrunning the other.

3. A rotary engine comprising a rotatable primary piston provided with a plurality of chambers and ports therein, in combination 115 with an outer cylinder rotatable eccentrically with respect to the said piston, secondary pistons located and reciprocable in said chambers and defining a plurality of piston spaces, means for slidably connecting the outer ends of said secondary pistons to the cylinder to permit of the differential motion between the primary piston and the outer cylinder, and means for admitting fluid through said ports to said secondary chambers and piston spaces to force the secondary pistons into fluid tight engagement with the outer cylinder and to rotate said piston and outer cylinder. 120

4. A rotary engine comprising an outer 130

cylinder and a primary piston provided with a plurality of chambers and eccentrically mounted within said cylinder, in combination with a plurality of secondary pistons 5 slidably engaging the outer cylinder and mounted in said chambers, means for admitting a fluid behind said secondary pistons to force the same in fluid-tight contact with said outer cylinder, said means also adapt-

ed to admit fluid to said piston spaces to 10 rotate the said cylinder and means for connecting said secondary pistons to the outer cylinder whereby the pistons are held in a definite position with respect to said cylinder.

15

In testimony whereof I affix my signature in the presence of two subscribing witnesses.

ALFRED SCHWARZ.
